UNITED STATES PATENT OFFICE

LOUIS L. FARRAR, OF MERIDEN, CONNECTICUT, ASSIGNOR TO THE MILLER COMPANY, OF MERIDEN, CONNECTICUT, A CORPORATION OF CONNECTICUT

DESIGN FOR A SHADE OR REFLECTOR

Application filed September 12, 1931. Serial No. 41,077. Term of patent 3½ years.

To all whom it may concern:

Be it known that I, LOUIS L. FARRAR, a citizen of the United States of America, and a resident of Meriden, in the county of New Haven and State of Connecticut, have invented a new, original, and ornamental Design for a Shade or Reflector, of which the following is a specification, reference being had to the accompanying drawing forming a part hereof.

In the drawings:

The shade or reflector may be used pendant or upright, as desired.

I claim:

The ornamental design for a shade or reflector, substantially as shown.

LOUIS L. FARRAR.
